UNITED STATES PATENT OFFICE

CHARLES ERIN COLE, OF CRIPPLE CREEK, COLORADO

PAPER WEIGHT

Application filed December 3, 1929. Serial No. 411,333.

This invention relates to a paper weight, one of the objects being to provide a device of this character which can be used for holding different specimens of natural products which will be associated with means whereby they can be identified readily, the entire structure being particularly useful as a means for advertising the resources of a locality.

Another object is to provide a device of this character which acts as a magnifying lens whereby the contents will be magnified so as to be more readily inspected.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred forms of the invention have been shown.

In said drawings,

Figure 1 is a central vertical section through the device.

Figure 2 is a top plan view.

Referring to the figures by characters of reference, 6 designates a pyramidal body formed in its base with an annular series of segmental recesses 7 arranged about a core 8 and gradually varying in depth toward their inner ends. The recesses are closed by a disk 9 extending under all of them and the several recesses can be filled with specimens of ores and the like as illustrated at 10. This structure is advantageous because of its capacity and because it presents extensive areas of specimens for observation. Different kinds of ores can be arranged in the different pockets and while the weight of the body and its contents renders the device particularly useful as a paper weight, the arrangement of the contents gives the device an educational value. By making the body so that it can act as a magnifying lens the study of the contents can be facilitated.

What is claimed is:

A paper weight including a magnifying glass constituting a body having separate non-communication recesses extending upwardly thereto from the bottom for holding specimens to be displayed and magnified, and a closure seated in the base of the magnifying glass for closing all of the recesses and retaining specimens therein, the several recesses increasing in depth but diminishing in width toward the center of the device thereby to constitute segmental containers.

In testimony that I claim the foregoing as my own, I have hereto affixed my signature.

CHARLES ERIN COLE.
